UNITED STATES PATENT OFFICE

2,092,504

SHIP CONSTRUCTION

Hugo P. Frear, New York, N. Y., assignor to
 Bethlehem Shipbuilding Corporation, Ltd., a
 corporation of Delaware

Application October 26, 1936, Serial No. 107,584

17 Claims. (Cl. 114—116)

My invention has reference to improvements in the design of the structural arrangement for stiffening and supporting the wall of a tank in a vessel especially designed to carry liquid cargo in bulk. It is more particularly an improvement on a ship structure such as is disclosed in my previous application Serial No. 731,239 which application issued as Patent 2,029,712 of February 4, 1936, and for which I have applied for a reissue, Serial No. 93,623, filed July 31, 1936.

In vessels of the type referred to it is common to have bottom, side, and deck plating, which together with abutting, or intersecting, transverse and longitudinal bulkheads subdivide the holds of the vessel into a multiplicity of tanks. These tanks when a vessel is in ballast are at times alternately loaded, some being full, while others are empty.

The construction of said tanks in a novel and efficient manner was the primary object of my above referred to previous application. It is the particular object of my present application to further improve upon the construction and means of supporting bulkheads in liquid cargo carrying vessels along the lines disclosed in said previous application but herein extended whereby such vessels may be more expeditiously and economically manufactured.

In my prior application no particular reference or claim was made to any specific form of subsidiary stiffeners for the bulkheads other than those of some conventional type shown in the drawings and briefly described in the specifications. It is a particular object of this my present application to provide an improved structural design specifically intended to replace the heretofore usual and conventional forms of subsidiary stiffeners or beams indicated in said application by employment of novel means equally effective structurally thereto and at the same time economical in weight of material required and in cost to manufacture.

It is an object of my invention to provide an improved substitute for the usual and conventional commercial rolled steel structural shapes usually used as subsidiary stiffeners in ship construction but otherwise supported as in said application. Such substitution consists in employing a fluted form of subsidiary stiffener comprised of a troughed plate, rolled, pressed, or otherwise formed, having an open face coincident with, or substantially so, the normal plane of said bulkhead, or its plating.

It is an object of my invention that said fluted form of stiffener shall be equal to in mechanical

effectiveness and shall be interchangeable therewith the heretofore usually provided commercial rolled steel stiffener when similarly used.

In my above mentioned prior application it was assumed that a bulkhead when under load is subjected to a fluid pressure load over its entire surface and that such surface was the entire area of the bulk head plating. This area was then conceived to be sub-divided into quite clearly defined main load sustaining areas which were most efficiently supported and stiffened when treated independently as such rather than if the entire area of the bulkhead were treated in the usual conventional way as a unit. In my said prior application I disclosed, described, and claimed a structure supporting an area by means of spaced girders supported at their ends by two oppositely disposed walls, and a plurality of commercial stiffeners supported by said girders transversely thereto having their ends jutting beyond their respective points of support on their adjacent girder.

It is also an object of this invention to extend said substitution to the stiffening beams of other said conceived load sustaining areas as may be considered desirable by any one skilled in the art.

It is also an object of this invention to extend said substitution to the stiffening beams of longitudinal bulkheads.

The novel features will be more fully understood from the following description and claims taken with the drawings, in which:

Fig. 1 represents diagrammatically a front elevation of a wing transverse bulkhead and of a middle transverse bulkhead embodying my invention;

Fig. 2 is a cross section taken along the line 2—2 of Fig. 1;

Fig. 3 is a cross section taken along the line 3—3 of Fig. 1;

Fig. 4 is similar to but a variation of Fig. 2, showing how commercial rolled steel shapes may be substituted for my fluted stiffeners;

Fig. 5 represents diagrammatically a front elevation of a longitudinal bulkhead embodying my invention;

Fig. 6 is a cross section taken along the line 6—6 of Fig. 5;

Fig. 7 is a modification of the middle transverse bulkhead shown in Fig. 1, showing a variation in the form of my fluted stiffeners;

Fig. 8 is a cross section taken along the line 8—8 of Fig. 7;

Fig. 15 is a cross section taken along the line 15—15 of Fig. 13;

Fig. 16 represents diagrammatically still another modification of a front elevation of a wing transverse bulkhead and of a middle transverse bulkhead similar to that shown in Fig. 13 but showing a variation in the form of my fluted stiffeners;

Fig. 17 is a cross section taken along the line 17—17 of Fig. 16; and

Fig. 18 is a cross section taken along the line 18—18 of Fig. 16.

For the purpose of a better understanding throughout this specification, I prefer the use of the following nomenclature relating to the supporting and stiffening of bulkheads wherein:—"Webs" are girders or principal members widely spaced which provide the main support direct from the walls or the bulkheads; "Beams" are secondary members usually widely spaced, supported by webs, and supporting in turn stiffeners; and, "Stiffeners" are subsidiary members usually closely spaced supported by webs or beams and chiefly contributing stiffeners or rigidity to the plating of the bulkheads. "Functionally integral" will be descriptive of a unitary structure whether formed of a single piece or a unit comprising a plurality of parts welded, riveted, or otherwise suitably attached one to another. "Structurally integral" will be descriptive of a unitary structure formed of a single piece. Also, the term "coincident" and associated terms where used herein to describe one portion of the bulkhead plating with respect to another portion thereof is to be understood to include in its reference the relationship of flat plates joined together by means of a lap joint. "Walls", where used in connection with bulkheads will be interpreted broadly as any closing side of the vessel as a whole, or of a room, or of a tank within the vessel. The term "Extended ends" or "Jutted ends" will be used in the description of a stiffener or beam supported at two or more points where the ends project beyond their nearest support in the form of a cantilever or an overhung beam with unsupported ends.

Also, with respect to the drawings it is to be understood that only the more essential elements are indicated, and that where a view is partially shown that which is omitted is readily comprehended by what is shown when regarded by those skilled in the art.

Referring now to Figs. 1, 2, and 3 which illustrate the embodiment of my invention as applied to the transverse bulkheads of a liquid cargo carrying vessel, the vessel is shown diagrammatically to comprise the deck 30, the sides 31, the bottom 32, the longitudinal bulkhead 33, the

wing transverse bulkhead 34, and the middle transverse bulkhead 35.

A wing transverse bulkhead 34 comprises the bulkhead plate 36 suitably attached at its periphery to the vessel's deck 30, side 31, bottom 32, and longitudinal bulkhead 33 by any conventional means such as the boundary angles 37. The horizontal webs 38 and the stiffener 39 are suitably attached to the bulkhead plate 36 and are suitably attached to and supported by the vessel's side 31 and longitudinal bulkhead 33. The brackets 40 and 41 are suitably attached to the bulkhead plate 36 opposite to the webs 38 and their function is to add support and continuity to the longitudinal bulkhead 33. The brackets 42 are functionally integral with the webs 38 and are suitably attached to and supported by the side 31. As shown the bulkhead plate 36 is provided with vertical flutes 43. These flutes 43 may be rolled, pressed, or otherwise integrally formed in the bulkhead plate 36. These flutes 43 function as stiffeners supported by the webs 38, into which they are fitted, and they support and give rigidity to the bulkhead plate 36, which they are an integral part, with effectiveness equal to that obtained were conventional commercial rolled steel stiffeners similarly used on a continuous flat plate 36. The ends of the flutes 43 act in cantilever fashion as they extend, or jut, beyond their nearest adjacent supporting web 38 by reason of being stopped substantially short of the deck 30 and of the bottom 32.

The middle transverse bulkhead 35 comprises the bulkhead plate 44 suitably attached to the vessel's deck 38, longitudinal bulkheads 33, and bottom 32 by any conventional means such as the boundary angles 45. The vertical webs 46 are suitably attached to the bulkhead plate 44 and are suitably attached to and supported by the vessel's deck 30 and bottom 32. The subsidiary stiffener 47 is suitably attached to the bulkhead plate 44 and is supported by and suitably attached to the webs 46. The subsidiary stiffener 48 is suitably attached to the bulkhead plate 44 and is supported by and suitably attached to the longitudinal bulkheads 33 and the webs 46. As shown the bulkhead plate 44 is provided with the horizontal flutes 49 and the vertical flutes 50. These flutes are similar to the flutes 43 and similarly they may be rolled, pressed, or otherwise integrally formed in the bulkhead plate 44. The flutes 49 function as stiffeners supported by the webs 46, into which they are fitted, and they support and give rigidity to a main central portion of the bulkhead plate 44. The flutes 50 also function as stiffeners supported by the brackets 51, and they support and give rigidity to the wall areas adjacent the longitudinal bulkheads. It will be noted that the ends of all the stiffeners 49 and 50 extend beyond their nearest adjacent points of support and that they are substantially short of that adjacent one of the boundary walls to which it is longitudinally opposed. The brackets 51 are suitably attached to the bulkhead plate 44 and are suitably attached to and supported by the longitudinal bulkheads 33. By having the brackets 51 in alignment with and opposite the inner ends of the wing bulkhead webs 38 the desired support or constraint is obtained for said brackets. The horizontal panels of plating 44 above and below the flutes 49 and 50 and of plating 36 below the ends of the flutes 43 are of increased width to provide for the passage of pipes, and the said panels may be locally stiffened by any type of stiffener as indicated by 39, 41, and 47.

48, or otherwise, as one skilled in the art may decide.

Fig. 4, I use to show the interchangeability and equivalency of my fluted stiffeners with the usual conventional forms comprised of commercial rolled steel sections. Here the middle transverse bulkhead 52 is identical with the bulkhead 35 of Fig. 1 with the exception of the vertical flutes, or fluted stiffeners 50. In substitution for each fluted stiffener 50 I show a pair of channel stiffeners 53 which may be so proportioned as to be the equivalent in physical properties and structural effectiveness as the flute 50 of the bulkhead plate 44. It will now be apparent that I could in the same manner substitute similar conventional type stiffeners for any or all of the flutes 43, 49, or 50.

Referring now to Figs. 5 and 6, I show the embodiment of my invention as applied to the longitudinal bulkheads of the same vessel as indicated in Figs. 1, 2, and 3. I have as in Fig. 1 the deck 30, the bottom 32, the wing transverse bulkheads 34, and the middle transverse bulkheads 35 which frame and define a longitudinal bulkhead panel 54 and which are suitably attached thereto by any conventional means such as the boundary angles 37 and 55. The longitudinal bulkhead panel 54 comprises the bulkhead plate 56. The vertical webs 57 are suitably attached to the bulkhead plate 56 and are suitably attached to and supported by the vessel's deck 30 and bottom 32. The subsidiary stiffeners 58 and 59 are suitably attached to the bulkhead plate 56 and are only to be regarded as stiffeners for which flutes are preferably not substituted. As shown the bulkhead plate 56 is provided with the horizontal flutes 60 substantially similar in structure to the flutes 43, 49, and 50. The flutes 60 function as stiffeners supported by the webs 57, into which they are fitted, and they support and give rigidity to the main central portion of the bulkhead plate 56.

Referring now to Figs. 7, 8, and 9, I show an embodiment of my invention as applied to a middle transverse bulkhead. It differs from that shown in Fig. 1 in having all the flutes used as stiffeners disposed in a vertical and parallel relationship, and in having the bulkhead plate built up of a plurality of parts as I will now describe. The middle transverse bulkhead 61 comprises the bulkhead plate 62 suitably attached to the vessel's deck 30, longitudinal bulkheads 33, and bottom 32 by any conventional means such as the boundary angles 63. The vertical webs 64 are suitably attached to the bulkhead plate 62 and are suitably attached to and supported by the vessel's deck 30 and bottom 32. The beams 65 are suitably attached to the bulkhead plate 62 and are suitably attached to and supported by the webs 64. The beams 65 have their ends extending, or jutting, beyond their nearest adjacent supporting web 64 but are stopped substantially short of the longitudinal bulkheads 33. In this modification the bulkhead plate 62 instead of having its fluted stiffeners pressed integrally into a single plate, as in Fig. 1, comprises the marginal plates 66 and 67, the fluted plate 68 and the flute end cover plates 69. The fluted plate 68 has a series of flutes 70 rolled or pressed transverse thereof so that its general cross section is constant for the full width thereof and may be said to comprise the elements 71 connected to the elements 72 by the sloping side elements 73. The upper and lower edges of the elements 71 overlap the inner edges 75 of the marginal plates 66 and 67 respectively

and are suitably attached to one another as by welding. The ends of the flutes 70 are closed by the cover plates 69 suitably attached thereto and to the marginal plates 66 and 67 as by welding. In the joining together of the various parts that go to make up the unit bulkhead plate 62 the joints so required whether by riveting, or as preferred, by welding shall be watertight. In the structure just described the elements 71 may be said to be in a plane coincident with that of the marginal plates 66 and 67, so that the structure of the bulkhead plate 62 as a whole is broadly the equivalent to one in which the flutes are formed integral in a single plate, as was shown in the bulkhead plates 36 and 44. As shown in Fig. 7, 15 the flutes 70 comprise the two end ones which I designate specifically as flutes 74. Flutes 74 are similar in function to the flutes 50 of Fig. 1 and are similarly suitably attached to and supported by the brackets 15. The central group of five 20 flutes 10 (as shown) are suitably attached to and supported by the beams 65. All the flutes 70 function as supported stiffeners and have their ends extending, or jutting, beyond their nearest point of support. The subsidiary stiffener 76 is 25 suitably attached to the front face of the marginal plate 67 and is supported by and suitably attached to the longitudinal bulkheads 33 and the webs 64.

Referring now to Figs. 10, 11, and 12 I show an embodiment of my invention as applied to a modification of a middle transverse bulkhead similar to that shown in Figs. 7, 8, and 9. Here the middle transverse bulkhead 77 comprises the bulkhead plate 78 suitably attached to the vessel's deck 79, longitudinal bulkheads 80, and bottom 81 by any conventional means such as the boundary angles 82. The vertical webs 83 are suitably attached to the bulkhead plate 78 and are suitably attached to and supported by the vessel's deck 79 and bottom 81. The beams 84 are suitably attached to the bulkhead plate and differ from the beams 65 of Fig. 7 in that they extend unbroken between the longitudinal bulkheads 80, and are supported by and suitably attached to the said bulkheads 80 and the webs 83. The bulkhead plate 78 comprises the marginal plates 85 and 86, the fluted plate 87, and the flute end cover plates 88 and 89. Here the cover plates 88 and 89 each cover a plurality of flute ends. Otherwise the fluted plate 87 is identical in structure to that shown in Figs. 7, 8, and 9. Here, as before described, the flutes function as supported stiffeners and have their ends extending beyond their adjacent supporting beam. Here the marginal plates 85 and 86 are deeper in proportion to those previously shown for reasons stated in connection with Fig. 1. The subsidiary stiffeners 90 and 91 are provided to give them required strength and rigidity and are of the same relative importance as stated for stiffeners 48 in connection with Fig. 1.

In Figs. 13, 14, and 15, I show another modification embodying certain features of my invention and further illustrating the interchangeability of design as between my fluted type of jutted end stiffener and the use of commercial rolled steel shapes as jutted end stiffeners. In Figs. 13, 14, and 15 I show a similar arrangement of stiffeners as is shown in the wing transverse bulkhead of Fig. 1 and in the middle transverse bulkhead of Fig. 7. In Figs. 13, 14, and 15, I show vertical stiffeners 92 comprised of standard rolled steel channels substituted for the fluted stiffeners 43 of Fig. 1 and 70 of Fig. 7. The webs 93 are identical with the webs 38 of Fig. 1 except for the necessary 75

change for the fitting-in of the stiffeners. The beams 94 differ from the beams 65 of Fig. 7 in that they extend continuous between the bulkhead walls 33 in a similar manner to the beams 84 of Fig. 10. The bulkhead plates 95 and 96, here shown are flat, and differ therein, of course, from the integral fluted bulkhead plate 36 of Fig. 1 and from the built up fluted bulkhead plate 62 of Fig. 7. The feature in these Figs. 13, 14, and 15 that embodies my invention is of having the ends of the stiffeners 92 extending, or jutting, beyond their adjacent points of support but substantially short of the adjacent wall supporting the bulkhead.

Coming now to Figs. 16, 17, and 18, I show an embodiment of my invention as applied to a modification of the wing transverse bulkhead shown in Fig. 1 and of the middle transverse bulkhead shown in Fig. 7. This modification varies from those just referred to mainly in the manner in which the bulkhead plate is built up of a plurality of parts to comprise when assembled fluted stiffeners equivalent to those shown in either Fig. 1 or Fig. 7. As in Figs. 1 and 7, I show in Figs. 16, 17, and 18 the vessel's deck 30, sides 31, bottom 32, and longitudinal bulkheads 33. I show also the wing transverse bulkhead 97 and the middle transverse bulkhead 98.

The wing transverse bulkhead 97 comprises the bulkhead plate 99 suitably attached at its periphery to the vessel's deck 30, side 31, bottom 32, and longitudinal bulkhead 33 by any conventional means such as the boundary angles 37. The horizontal webs 100 and the stiffener 101 are attached to the bulkhead plate 99 and are suitably attached to and supported by the vessel's side 31 and longitudinal bulkhead 33. The bulkhead plate 99 comprises the top marginal plate 102, the side marginal plates 103 and 104, the bottom marginal plate 105, the fluted stiffeners 106, and the flute end cover plates 107. The fluted stiffeners 106 are fitted in and supported by the webs 100 with their ends jutted beyond their nearest web 100. A fluted stiffener 106 may be a rolled or pressed section, or otherwise integrally formed, and is comprised of the wall 108, the side walls 109 and 110, and the flanges 111 and 112. It is my intention that the fluted stiffeners 106 may be joined together, as by welding, one to another and to the side marginal plates 103 and 104. When thus assembled the marginal plates 103 and 104 together with the fluted stiffeners 106 form a fluted plate 113 similar in use to the fluted plate 68 described in connection with Fig. 7. It is desirable that when so assembled that the fluted plate 113 have a face at the upper and lower edges thereof in a common plane for convenience in attaching, as by lap welded joints, to the inner edges of the marginal plates 102 and 105. To meet this desideratum I prefer to make the wall 109 of the fluted stiffener 106 longer by the amount of the thickness of the plate used than the wall 110. In this way when the stiffeners 106 are joined together one with another and to the side marginal plate 104 the faces thereof are in a common plane. In order to complete the desideratum as far as side marginal plate 103 is concerned I prefer to use a filler piece 114 at each end of the side marginal plate 103 to have the full width of the fluted plate 113 at its edges in a common plane. The flute end cover plates 107 are preferably welded to the ends of the fluted stiffeners 106 and to the marginal plates 102 and 105. All the joints making up

the unit bulkhead plate 99 should be watertight.

The middle transverse bulkhead 115 is similar in construction to that just described for the wing transverse bulkhead 97 and will be readily comprehended by what has been described herein before without further detail description. The middle transverse bulkhead 115 comprises the bulkhead plate 116 suitably attached to the vessel's deck 30, longitudinal bulkheads 33, and bottom 32 as by angles 117. The vertical webs 118 are suitably attached to the bulkhead plate 116 and are suitably attached to and supported by the vessel's deck 30 and bottom 32. The beams 119 are suitably attached to the bulkhead plate 116 and are suitably attached to and supported by the webs 118. The beams 119 have their ends jutting beyond their nearest point of support (webs 118) but substantially short of the bulkheads 33. The stiffener 120 is similar to 48 in Fig. 1 and is suitably attached to the bulkhead plate 116 and is supported by and suitably attached to the bulkheads 33 and the webs 118. The bulkhead plate 116 comprises the top marginal plate 121, the side marginal plate 122, the bottom marginal plate 123, the fluted stiffeners 124, and the flute end cover plates 125. The fluted stiffeners 124 are identical to the fluted stiffeners 106 and need not be further described. It will be noted that here no marginal plate is required on the left side and therefore no filler piece is required. Also if desired a special section might be used on the righthand side in which the side marginal plate 122 would be integral therewith. The two end ones of the fluted stiffeners 124 are supported by the brackets 126 and have their ends jutted beyond their nearest supporting bracket. The brackets 126 are attached to and supported by the bulkheads 33.

In all the arrangements in which the fluted stiffeners have been shown and described up to this point they have been shown and described in the preferred form in which the flute is formed in the bulkhead plate toward its supporting webs, beams, or brackets, with its open face on the rear face of said bulkhead plate. However, it is apparent that the direction of facing of these flutes could be reversed without departing from the scope of my invention. To illustrate this point I show in dotted lines reversed flutes 127 applied to Fig. 3. It is equally applicable to the types of flutes shown in Figs. 7 and 16. It is equivalent to stating that the supporting webs, beams, and/or brackets may be applied to either side of the bulkhead plates as shown.

In Figs. 10 and 12, I show a modification to my multiple fluted plate of preferred use when it is desirable to attach multiple fluted sections one to another. The multiple fluted plate 128 comprises the walls 129, the walls 130, the connecting walls 131, the left flange 132, and the right flange 133. It will be noted that the rear face of the right flange 133 is in facial alignment with the front face of the left flange 132. In this manner when I wish to join two or more multiple fluted plates together, such as the plate 128 to the plate 134, the joining flanges 133 of the plate 128 and 135 of the plate 134 overlap one another, so that in the assembled relationship of the two plates all the faces of the rear walls are in facial alignment, convenient for suitable attachment one to another and to the upper and lower marginal plates 85 and 86 respectively.

Generally speaking it is preferred, for con-

venience of substitution, that the pitch distance between two adjacent flutes be approximately 60" and that the mean width of a flute be approximately 30" to agree with the most common spacing of ordinary stiffeners.

From the foregoing description it will now be readily recognized by those skilled in the art that I have a novel method of ship construction which is particularly economical of weight without any sacrifice in efficiency or strength. It is also apparent that I have followed the principles taught in my said prior application, and herein extended, for supporting and stiffening bulkheads, and as particularly set forth herein as the object of my invention. I have shown and described a variety of arrangements for the supporting and stiffening of bulkheads but each arrangement has comprised a stiffener characterized by being supported by a web, beam, or bracket in such a manner that an end juts, or extends, beyond its nearest of said supports toward one of the bulkhead boundary walls but substantially short thereof. Also, the said stiffener in each case is characterized by structure whereby it enters into the main plating of the bulkhead as an integral flute therein, or functionally integral thereon by attachment.

I do not wish it to be understood that my above described methods are limited in their application to vessels of the type described and it is manifest that the principle of design herein set forth could be utilized with other well known types of ship construction.

The terms and expressions which I have employed are used as terms of description and not of limitation and I have no intention, in the use of such terms and expressions, of excluding any equivalents of the features thereof, but recognize that various modifications are possible within the scope of the invention claimed.

Having thus described my invention what I claim as new and desire to secure by Letters Patent is:

1. In a ship structure, a rectangular load sustaining wall, four boundary walls normal to said load sustaining wall, and spaced supporting means attached to one of said boundary walls, the said load sustaining wall comprising a plate having functionally integral therewith a relatively long and narrow closed end fluted recessed portion supported at points on said supporting means, the ends of said fluted recessed portion extending beyond its respective points of support on its adjacent supporting means but substantially short of the said boundary walls normal to the said supporting wall respectively.

2. In a ship structure, a rectangular load sustaining wall, four boundary walls normal to said load sustaining wall, and spaced webs supported at their ends by two oppositely disposed of said boundary walls, the said load sustaining wall comprising a plate having functionally integral therewith a relatively long and narrow closed end fluted recessed portion transverse to and supported at points on said webs, the ends of said fluted recessed portion extending beyond its respective points of support on its adjacent web but substantially short of the two remaining of said boundary walls respectively.

3. In a ship structure, a rectangular load sustaining wall, four boundary walls normal to said load sustaining wall, and spaced webs supported at their ends by two oppositely disposed of said boundary walls, said load sustaining wall comprising a plate having functionally integral there-

with a plurality of relatively long and narrow parallel closed end fluted recessed portions transverse to and supported at points on said webs, the ends of said fluted recessed portions extending beyond their respective points of support on their adjacent web but substantially short of the two remaining of said boundary walls respectively. 5

4. In a ship structure, a rectangular load sustaining wall, four boundary walls normal to said load sustaining wall, and spaced webs supported at their ends by two oppositely disposed of said boundary walls, said load sustaining wall comprising a plurality of plates each having functionally integral therewith a relatively long and narrow closed end fluted recessed portion transverse to and supported at points on said webs, the ends of said fluted recessed portions extending beyond their respective points of support on their adjacent web but substantially short of the two remaining of said boundary walls respectively. 10 15

5. In a ship structure, a rectangular load sustaining wall, four boundary walls normal to said load sustaining wall, spaced webs supported at their ends by two oppositely disposed of said boundary walls, a plurality of beams supported by said webs transversely thereto having their ends substantially short of the two remaining of said boundary walls respectively, and a plurality of stiffeners attached to said load sustaining wall supported at points on said beams transversely thereto, the ends of said stiffeners extending beyond their respective points of support on their adjacent beam but substantially short of the first mentioned two of said boundary walls respectively. 25 30 35

6. In a ship structure, a rectangular load sustaining wall, four boundary walls normal to said load sustaining wall, spaced webs supported at their ends by two oppositely disposed of said boundary walls, and a plurality of beams supported by said webs transversely thereto having their ends substantially short of the two remaining of said boundary walls respectively, the said load sustaining wall comprising a plate having functionally integral therewith a plurality of relatively long and narrow parallel closed end fluted recessed portions transverse to and supported at points on said beams, the ends of said fluted recessed portions extending beyond their respective points of support on their adjacent beam but substantially short of the first mentioned two of said boundary walls respectively. 40 45 50

7. In a ship structure, a rectangular load sustaining wall, four boundary walls normal to said load sustaining wall, spaced webs supported at their ends by two oppositely disposed of said boundary walls, and a plurality of beams supported by said webs transversely thereto having their ends substantially short of the two remaining of said boundary walls respectively, the said load sustaining wall comprising a plurality of plates each having functionally integral therewith a relatively long and narrow closed end fluted recessed portion transverse to and supported at points on said beams, the ends of said fluted recessed portions extending beyond their respective points of support on their adjacent beam but substantially short of the first mentioned two of said boundary walls respectively. 55 60 65 70

8. In a ship structure, a rectangular load sustaining wall, four boundary walls normal to said load sustaining wall, spaced webs supported at their ends by two oppositely disposed of said

75

- boundary walls, a plurality of stiffeners attached to said load sustaining wall and supported at points on said webs transversely thereto, spaced supporting means attached to each of the two 5 remaining of said boundary walls, and stiffeners attached to said load sustaining wall and supported at points on said supporting means parallel to said webs, the ends of each of all said stiffeners extending beyond their respective adjacent points of support but substantially short of the boundary wall to which they are individually longitudinally opposed.
9. In a ship structure, a rectangular load sustaining wall, four boundary walls normal to said 15 load sustaining wall, spaced webs supported at their ends by two oppositely disposed of said boundary walls, and spaced supporting means attached to each of the two remaining of said boundary walls, the said load sustaining wall 20 comprising a plate having functionally integral therewith a plurality of relatively long and narrow closed end fluted recessed portions, certain of said recessed portions being transverse to and supported at points on said webs and certain 25 other of said recessed portions being parallel to said webs and supported at points on said supporting means, the ends of each of all said fluted recessed portions extending beyond their respective adjacent points of support but substantially 30 short of the boundary wall to which they are individually longitudinally opposed.
10. In a ship structure, a rectangular load sustaining wall, four boundary walls normal to said load sustaining wall, spaced webs supported at 35 their ends by two oppositely disposed of said boundary walls, a plurality of beams supported by said webs transversely thereto having their ends substantially short of the two remaining of said boundary walls respectively, a plurality of 40 stiffeners attached to said load sustaining wall supported at points on said beams transversely thereto and parallel to said webs, spaced supporting means attached to each of the second mentioned two of said boundary walls, and stiffeners attached to said load sustaining wall and supported at points on said supporting means 45 parallel to said webs, the ends of each of all said stiffeners extending beyond their respective adjacent points of support but substantially short of the boundary wall to which they are individually 50 longitudinally opposed.
11. In a ship structure, a rectangular load sustaining wall, four boundary walls normal to said load sustaining wall, spaced webs supported at 55 their ends by two oppositely disposed of said boundary walls, a plurality of beams supported by said webs transversely thereto having their ends substantially short of the two remaining of said boundary walls respectively, and spaced supporting means attached to each of the second 60 mentioned two of said boundary walls, the said load sustaining wall comprising a plate having functionally integral therewith a plurality of relatively long and narrow closed end fluted recessed portions, certain of said recessed portions being transverse to and supported at points on said webs and certain 65 other of said recessed portions being parallel to said webs and supported at points on said supporting means, the ends of each of all said fluted recessed portions extending beyond their respective adjacent points of support but substantially short of the boundary wall to which they are individually 70 longitudinally opposed.
12. In a ship structure, a rectangular load sustaining wall, four boundary walls normal to said load sustaining wall, spaced webs supported at 75 their ends by two oppositely disposed of said boundary walls, a plurality of beams supported at their ends by the two remaining oppositely disposed of said boundary walls and intermediate thereof by the said webs transversely thereto, and a plurality of stiffeners attached to said load sustaining wall supported at points on said beams transversely thereto, the ends of said stiffeners extending beyond their respective points of support on their adjacent beam but substantially short of the first mentioned two of said boundary walls respectively.
13. In a ship structure, a rectangular load sustaining wall, four boundary walls normal to said load sustaining wall, spaced webs supported at 15 their ends by two oppositely disposed of said boundary walls, and a plurality of beams supported at their ends by the two remaining oppositely disposed of said boundary walls and intermediate thereof by the said webs transversely thereto, the said load sustaining wall comprising a plate having functionally integral therewith a plurality of relatively long and narrow parallel closed end fluted recessed portions transverse to and supported at points on said beams, the ends of said fluted recessed portions extending beyond their respective points of support on their adjacent beam but substantially short of the first mentioned two of said boundary walls respectively.
14. In a ship structure, a rectangular load sustaining wall, four boundary walls normal to said load sustaining wall, spaced webs supported at 20 their ends by two oppositely disposed of said boundary walls, and a plurality of beams supported at their ends by the two remaining oppositely disposed of said boundary walls and intermediate thereof by the said webs transversely thereto, the said load sustaining wall comprising a plate having functionally integral therewith a plurality of relatively long and narrow parallel closed end fluted recessed portions transverse to and supported at points on said beams, the ends of said fluted recessed portions extending beyond their respective points of support on their adjacent beam but substantially short of the first mentioned two of said boundary walls respectively.
15. In a ship structure, a rectangular load sustaining wall, four boundary walls normal to said load sustaining wall, spaced webs supported at 25 their ends by two oppositely disposed of said boundary walls, and a plurality of beams supported at their ends by the two remaining oppositely disposed of said boundary walls and intermediate thereof by the said webs transversely thereto, the said load sustaining wall comprising a plate having functionally integral therewith a relatively long and narrow closed end fluted recessed portion transverse to and supported at points on said beams, the ends of said fluted recessed portions extending beyond their respective points of support on their adjacent beam but substantially short of the first mentioned two of said boundary walls respectively.
16. In a ship structure, a load sustaining wall, boundary walls normal to said load sustaining wall, a plurality of stiffeners attached to said load sustaining wall, and means attached to said boundary walls comprising spaced points of support for said stiffeners, the said stiffeners extending beyond their respective points of support on said means but substantially short of the boundary wall to which they are individually longitudinally opposed.
17. In a ship structure, a rectangular load sustaining wall, boundary walls normal to said load sustaining wall, the said load sustaining wall comprising plating having functionally integral therewith a plurality of relatively long and narrow closed end fluted recessed portions, and means attached to said boundary walls comprising spaced points of support for said fluted recessed portions, the said fluted recessed portions extending beyond their respective points of support on said means but substantially short of the boundary wall to which they are individually longitudinally opposed.

comprising plating having functionally integral therewith a plurality of relatively long and narrow closed end fluted recessed portions, and means attached to said boundary walls comprising spaced points of support for said fluted recessed portions, the said fluted recessed portions

extending beyond their respective points of support on said means but substantially short of the boundary wall to which they are individually longitudinally opposed.
